UNITED STATES PATENT OFFICE

RALPH S. KELSO, OF ROCKFORD, ILLINOIS, ASSIGNOR TO THE FREE SEWING MACHINE COMPANY, OF ROCKFORD, ILLINOIS, A CORPORATION OF ILLINOIS

BOBBIN WINDER

Application filed February 6, 1930. Serial No. 426,406.

This invention relates to bobbin winders for sewing machines.

An important object of the invention is to provide a novel and readily operable bobbin winder adapted to be driven through the medium of the hand wheel of the sewing machine.

A further object is to provide a bobbin winder having a friction driving element associated therewith and adapted to be brought into driving engagement with the hand wheel of the sewing machine, and to provide novel means for releasing the driving connection referred to after the bobbin is filled.

A further object is to provide novel latch mechanism for holding the device in operative position with the driving element in engagement with the hand wheel of the machine, and to provide means operative when the bobbin is full for automatically releasing the latch and permitting the parts of the bobbin winder to return to their normal inoperative positions.

A further object is to provide a bobbin winder of the character just referred to having resilient means for maintaining the driving element of the bobbin winder in engagement with the hand wheel of the machine.

A further object is to provide a compound lever device including a pair of arms pivotally connected to each other and relatively movable and to provide resilient means associated with one of the arms for holding a driving element carried thereby in frictional engagement with the hand wheel of the machine to rotate the bobbin during the winding operation.

A further object is to provide a device of the character just referred to wherein the friction driving member is carried by one of the relatively movable arms and a latch mechanism is carried by the other arm to retain the parts in operative position, automatic means being operable when the bobbin is full for releasing the latch and permitting the parts to return to normal position.

Other objects and advantages of the invention will become apparent during the course of the following description.

In the drawings I have shown one embodiment of the invention. In this showing,

Figure 1 is a front elevation of a sewing machine showing the device applied,

Figure 2 is an end elevation of the same, 55

Figure 3 is an enlarged detail face view of the device,

Figure 4 is a detail perspective view of the latch lever, and,

Figure 5 is a similar view of one of the 60 spring members.

Referring to the drawings the numeral 10 designates a sewing machine as a whole including a bed 11 having a head of any type carried thereby and including a standard 12 65 and a horizontal arm 13. The sewing machine illustrated includes a motor 14 adapted to drive the hand wheel 15 through a suitable frictional power transmission indicated as a whole by the numeral 16. 70

A spool of thread 17 is illustrated as being mounted upon the usual post 18, and when it is desired to wind a bobbin, the thread from the spool is passed around a guide 19 of any suitable type. One of the bobbins is illustrated by the numeral 20 in operative position on the bobbin winder to be referred to, and the thread from the guide 19 is led downwardly around the bobbin to be wound thereon as will be apparent. The elements of the 80 sewing machine previously described form no part of the present invention and may be of any desired type. 75

The guide 19 is carried by the upper end of a supporting member indicated as a whole 85 by the numeral 21 and includes a lower end portion 22 secured against the outer face of the standard 12 by screws 23 and 24. The lower portion 22 of the supporting member constitutes a plate adapted to carry the elements of the bobbin winder to be referred to, and the upper edge of this plate is provided with a latch tooth 25. 90

A pair of arms 26 and 27 form a compound lever pivotally connected to each other by a screw 28, as shown in Figures 2 and 3. The lower end of the arm 26 is pivotally connected to the plate 22 by the screw 24, and it will be apparent that the arms 26 and 27 are adapted to swing together about the axis of 100

the screw 24, but that they are adapted to partake of turning movement with respect to each other about the axis of the screw 28. The arm 26 is provided with a lug 29 adapted to contact with a pin 30 carried by the plates 22 to limit the outward and downward turning movement of the compound lever about the axis of the screw 24.

Resilient means is employed for normally swinging the compound lever outwardly and downwardly to bring the lug 29 into contact with the pin 30. Referring to Figure 5, the numeral 31 designates a spring as a whole having an intermediate coiled portion 32 surrounding a portion of the shank of the screw 24 as indicated in dotted lines in Figure 3. One end 33 of the spring is hooked and passes around the pin 30 outwardly of the lug 29. The other end 34 of the spring 31 extends along the face of the arm 26 and is hooked at its extremity as at 35 to pass around a pin 36 extending outwardly from the arm 26. It will be apparent that the tension of the spring 31 is such as to exert a resilient force outwardly and downwardly against the pin 36, thus tending to swing the arm 26 in a counter-clockwise direction.

A spring indicated as a whole by the numeral 37 is adapted to urge the arm 27 in a clockwise direction around the axis of the screw 28 for a purpose to be described. This spring includes a central coiled portion 38 surrounding a portion of the shank of the screw 28, and the lower end of the spring is hooked as at 39 beneath the pin 36. The upper end 40 of the spring 37 passes through an opening 41 in the arm 27. It will be apparent that the spring 37 is tensioned to normally swing the upper end of the arm 27 upwardly and inwardly.

The upper end of the arm 27 is provided with a bearing 42 in which is journaled a shaft 43. A friction driving element 44 is carried by one end of the shaft 43 and is adapted to frictionally engage against the peripheral portion of the hand wheel 15 whereby rotation of the latter element is adapted to drive the shaft 43. Means (not shown) is provided for frictionally holding the bobbin 20 in place on the inner end of the shaft 43 whereby the bobbin is caused to rotate with the shaft during the operation of winding the thread upon the bobbin.

Beneath the screw 28 the arm 27 is provided with a lug 45 adapted to engage the pin 36 to limit the turning movement of the arm about the axis of the screw 28 when the driving element 44 is out of engagement with the hand wheel, as shown in Figure 3. It will be apparent that when the elements of the device are brought to operative position, as shown in Figure 2, the contacting of the friction element 44 with the hand wheel causes the arm 27 to swing outwardly, and the driving element 44 will be maintained in

driving engagement with the hand wheel 15 through the resilient force of the spring 37.

Means is provided for holding the elements of the device in the operative position referred to and for releasing the parts from such position after the bobbin has been wound. The numeral 46 designates a latch lever as a whole having an opening 47 intermediate its ends through which passes a screw 48 pivotally connecting the latch lever 46 to the arm 26. The inner end of the lever 46 is provided with a latch 49 adapted to engage the tooth 25 when the parts are in the operative position shown in Figure 2.

Between the pivot of the latch lever and the free end thereof, the lever is offset laterally as at 50 whereby the end portion 51 of the lever is arranged in the transverse vertical plane of the bobbin as shown in Figure 1. The end 51 of the latch lever is curved as shown in Figures 3 and 4 and is adapted to contact with the turns of the thread being wound upon the bobbin whereby the latch lever will be gradually moved as the depth of the thread on the bobbin increases.

Spring means is provided for normally holding the latch lever in the position indicated in Figures 2 and 3, with the end 51 of the lever in position ready to be engaged by the increasing turns of thread on the bobbin. A spring is turned about the pivot screw 48 and has one end 52 engaging in a notch 53 formed in the upper edge of the inner end of the latch lever. The opposite end 54 of the spring extends through a small opening formed in the pivoted arm 26. The spring for the latch lever is tensioned to move the outer end of the lever inwardly and upwardly and the inner end of the lever downwardly. A finger piece 55 extends laterally from the latch lever and is manually operable to move the lever against the tension of its spring when it is desired to move the parts to operative position.

The operation of the device is as follows:

The parts of the device normally occupy the position shown in Figure 3, and under such conditions, the lug 29 is in engagement with the pin 33, the lug 45 is in engagement with the pin 36, and the latch 49 is released from the tooth 25. When it is desirable to wind a thread upon the bobbin, the latter is placed in position on the inner end of the shaft 43 with the thread from the spool 17 passing around the guide 19, as shown in Figure 1.

The operator then presses upwardly and inwardly against the finger piece 55, and this operation moves the arms 26 and 27 upwardly and inwardly and causes the latch 49 to slide over the top of and to engage behind the latch tooth 25. Before the latch lever reaches its fully operative position, the driving element 44 will have engaged against the hand wheel 15, and as the latch 49 approaches op-

erative position, the arms 26 and 27 swing with respect to each other about the axis of the screw 28 and against the tension of the spring 37. Accordingly it will be apparent that the arm 26 and the latch lever will occupy fixed positions with respect to the plate 22, while the arm 27 is movable independently of these elements and is urged upwardly and inwardly to maintain the proper frictional driving engagement between the element 44 and the hand wheel 15.

The motor 14 is then started to drive the wheel 15, the wheel having previously been disconnected from its driving engagement with the sewing apparatus. The rotating movement of the hand wheel is transmitted to the driving element 44 to rotate the shaft 43, this movement in turn being transmitted to the bobbin 20 to wind the thread thereon.

As the turns of thread on the bobbin increase, the outer turns contact with the end 51 of the latch lever, and as the turns of thread further increase, they will gradually move the end of the latch lever outwardly and downwardly. This action obviously swings the latch lever gradually about its pivot 48, and the parts are so designed that when the proper amount of thread is wound on the bobbin, the latch arm will have turned a sufficient distance about its pivot to release the latch 49 from the tooth 25.

As previously stated, the spring 31 normally urges the arm 26 outwardly and downwardly, and accordingly the spring comes into operation as soon as the latch 49 is released from the tooth 25 and the arm 26 will be moved to operative position, the lug 29 contacting with the pin 30 to limit the turning movement of the arm. As the arm 26 starts its movement toward inoperative position, the driving element 44 will be momentarily held in engagement with the hand wheel until the lug 45 contacts with the pin 36, and continued turning movement of the arm 26 will then move the driving element out of engagement with the hand wheel. As soon as the parts have returned to inoperative position, the bobbin is ready to be moved from the shaft 43, as will be apparent.

From the foregoing it will be obvious that the latch lever performs three different functions in the apparatus in that the latch element 49 holds the device in operative position, the end 51 of the lever serves to automatically release the device for movement to inoperative position, and the finger piece serves as convenient means for moving the device to operative position. The use of a compound lever including the arms 26 and 27 permits all of the parts of the apparatus to be locked positively in operative position except those parts associated with the arm 27, and accordingly the spring 37 may be employed for resiliently holding such parts in operative position to secure the proper frictional driving engagement between the driving element 44 and the hand wheel 15. The device is simple in construction and readily movable, as will be apparent.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. A bobbin winder comprising a device pivotally supported at one end, a driving element carried by the other end of said device, said device including a pair of arms pivotally connected to each other, coacting means carried by said device and a sewing machine for locking one of said arms in operative position, means connected between said arms and operative when the last named arm is in operative position for holding said driving element in engagement with a rotating part of the sewing machine to be driven thereby, means connected to said driving element for supporting a bobbin, and means automatically operative when a predetermined amount of thread is wound on said bobbin for releasing said locking means to permit the parts of said device to return to inoperative position.

2. A bobbin winder comprising a compound lever device including a pair of arms pivotally connected to each other at their inner ends, means for supporting the free end of one of said arms with respect to a sewing machine to permit swinging movement of said lever device, a bobbin holder rotatably supported by the free end of the other arm, a friction driving element connected to said bobbin holder and movable with said lever device into frictional driving engagement with a rotatable part of the sewing machine, and means connected with said first named arm for holding said lever device in operative position with said driving element in driving position, and including a portion operative when a predetermined amount of thread is wound on said bobbin for releasing said holding means to permit said lever device to return to normal position with said driving element out of driving position.

3. A bobbin winder comprising a support connected to a sewing machine head and provided with a latch tooth, a compound lever device including a pair of arms pivotally connected to each other at their inner ends, means for pivotally connecting the free end of one of said arms with said support, a bobbin holder rotatably supported by the free end of the other arm, a friction driving element connected to said bobbin holder and movable with said lever device into frictional engagement with the hand wheel of the sewing machine, resilient means tending to move

said lever device as a whole away from the hand wheel, and latch means for holding said lever device in operative position with said driving element in driving engagement with the hand wheel, and including a portion operative when a predetermined amount of thread is wound on said bobbin for releasing said latch means to permit said resilient means to return said lever device to normal position.

4. A bobbin winder comprising a support connected to a sewing machine head and provided with a latch tooth, a pair of arms pivotally connected to each other at their inner ends, a pivot pin connecting the free end of one arm to said support, a bobbin holder rotatably supported by the free end of the other arm, a friction driving element connected to said bobbin holder and adapted to frictionally engage the hand wheel of the sewing machine, resilient means connected to the first named arm for moving it outwardly with respect to the hand wheel, resilient means tending to move the second named arm inwardly toward the hand wheel, means for limiting the last named movement, a latch carried by the first named arm and engageable with said latch tooth to hold said arms in operative position with said driving element in engagement with the hand wheel, and a member carried by said latch for releasing it and operative upon the accumulation of a given amount of thread on the bobbin.

5. A bobbin winder comprising a support connected to a sewing machine head and provided with a latch tooth, a pair of arms pivotally connected to each other at their inner ends, a pivot pin connecting the free end of one arm to said support, a bobbin holder rotatably supported by the free end of the other arm, a friction driving element connected to said bobbin holder and adapted to frictionally engage the hand wheel of the sewing machine, resilient means connected to the first named arm for moving it outwardly with respect to the hand wheel, resilient means tending to move the second named arm inwardly toward the hand wheel, means for limiting said last named movement, and an integral latch lever pivotally connected intermediate its ends to said first named arm and including a tooth adapted to engage said latch tooth to hold said arms in operative position against the tension of said first named resilient means with said driving element in engagement with said hand wheel, said latch lever being further provided with a member adapted to be acted upon by the thread accumulating on the bobbin for releasing the tooth of said latch lever from said latch tooth.

6. A device constructed in accordance with claim 5 provided with means for limiting the movement of said first named arm outwardly

with respect to the hand wheel, said last named limiting means being operative upon outward movement of the associated arm after the limiting means for the second named arm has come into operation.

7. A device constructed in accordance with claim 5 wherein said latch lever is provided with a finger piece operable for moving said arms to operative position and for engaging the tooth of said latch lever with said latch tooth.

8. A device constructed in accordance with claim 5 wherein said bobbin holder comprises a rotatable shaft, the free end of said second named arm being provided with a bearing in which said shaft is rotatably mounted.

9. A bobbin winder including a pair of arms each having an end pivotally connected together, a bracket including a hook adapted to be rigidly connected to a sewing machine, the free end of one arm being pivotally connected to said bracket, a latch member pivotally connected to said last named arm and adapted to engage said hook, a bobbin holder carried by the free end of the other arm, means engageable with a rotating part of the sewing machine for driving the bobbin holder, and resilient means connected between said arms for urging them out of alinement with each other whereby the means engageable with the rotating part of the sewing machine is urged toward such part and is engageable therewith when said latch or member is in engagement with said hook, said latch member having a projecting portion automatically operative to release the latch member from said hook when a predetermined amount of thread is wound on the bobbin.

In testimony whereof I affix my signature. 10
RALPH S. KELSO.
